[57] CLAIM

The ornamental design for a toggle light switch extension device, as shown and described.

DESCRIPTION

FIG. 1 is a left side elevational view of a toggle light switch extension device showing my new design, the undisclosed right side being a mirror image thereof;

FIG. 2 is a rear elevational view;

FIG. 3 is a bottom plan view thereof;

FIG. 4 is a top plan view; and

FIG. 5 is a rear perspective view thereof taken slightly from above.

The broken lines in FIG. 1 have been shown for illustrative purposes only.

FIG. 2

FIG. 1

FIG. 3

FIG. 4

FIG. 5
